UNITED STATES PATENT OFFICE.

ARTHUR E. WELLS, OF NEW YORK, N. Y.

COIN-CONTROLLED APPARATUS.

SPECIFICATION forming part of Letters Patent No. 760,502, dated May 24, 1904.

Application filed January 9, 1904. Serial No. 183,282. (No model.)

To all whom it may concern:

Be it known that I, ARTHUR E. WELLS, a citizen of the United States, residing at New York city, (Manhattan,) county and State of New York, have invented new and useful Improvements in Coin-Controlled Apparatus, of which the following is a specification.

This invention relates to a coin-controlled apparatus, such as a lung-tester, provided with improved means for preventing the machine from being worked by a succession of impulses.

In the accompanying drawings, Figure 1 is a front elevation of a coin-controlled apparatus embodying my invention and showing the same applied to a lung-tester; Fig. 2, a side elevation, partly in section, of the coin-controlled mechanism; Fig. 3, a front elevation thereof; Fig. 4, a view similar to Fig. 2, showing the parts in a different position; and Fig. 5, a detail of the mouth-tube and indicator.

The letter A represents the casing of the apparatus, within which is fitted a plate a, mounted upon a base a'. To plate a is fulcrumed at b' a beam b, having at one end an inclined upwardly-extending projection b² and a similar downwardly-extending projection b³. At its other end the beam b is pivotally connected at c' to a piston-rod c, the piston c² of which plays in a cylinder d, open at its top. A pin c³, adapted to engage the upper end of cylinder d, limits the descent of the piston, while a spring e tends to draw the latter into its lowermost position. Into the cylinder d enters an air-inlet tube f, having mouthpiece f', and an air-exit tube g, which is adapted to convey the exhaled air to a suitable indicator. This indicator is shown to consist of a bell h, movable within a casing h', so that the height to which the bell is raised will measure the volume of air admitted to the indicator.

At right angles to beam b there is fulcrumed to plate a at i a coin-operated three-arm lever I. One arm i' of lever I is arranged in the path of the coin B, which is introduced into a coin-chute A' of casing A. After the coin has tilted the lever it clears the same and falls into a suitable receptacle. (Not shown.) The second arm i'' of lever I is notched,

as at i³, to form a seat for beam b, which is adapted to lock the beam in its normal position. The third arm i⁴ of lever I carries a weight j, which tends to raise lever-arm i'' and to hold lever-arm i'' against beam b.

To a bearing a², projecting forwardly from plate a, is secured a pivot k, upon which is adapted to swing a frame or yoke L. This yoke is composed of two inclined parallel bars l, which are connected at or near their center by a tube l', that embraces pivot k. The upper ends of bars l are connected by a cross-arm l'', located between the projections b² b³ of beam b. The lower ends of bars l are disconnected from each other and carry each a counterweight m. To the tube l' of yoke L is rigidly secured a detent l'', having a nose l', which is by the weights m normally held against the front of lever I. When the lever I is tilted by a coin, the nose l' will pass underneath lever-arm i⁴, and thus hold lever-arm i'' off beam b.

The operation is as follows: Normally the piston c² is in its lowermost position and intermediate the inlet and exit tubes f g, so as to cut off the former from the latter, Fig. 2. In this position the beam b, and consequently the piston c², is locked by the engagement of the beam with the notch i³ of lever-arm i''. Upon the introduction of a coin B into the coin-chute A' the lever I is tilted so as to withdraw arm i'' from beam b. (Dotted lines in Fig. 3.) As the lever I is thus tilted it will clear the nose l' of detent l'' and will permit the weights m to swing the yoke L with its upper end rearward. This movement of the yoke will cause the nose l' to be projected underneath lever-arm i⁴ and to thus lock the lever I in its tilted position. In this position the notch i³ of arm i'' is out of engagement with beam b, so that the latter remains released. The tilting of yoke L will also have brought its cross-piece l'' in engagement with projection b² of beam b, (full lines in Fig. 4,) by which means the play of detent l'' l' is limited. Air may now be blown through tube f, the air raising piston c², (dotted lines in Fig. 4,) so that communication is established between tubes f and g, and the exhaled air may

operate the indicator. The raising of the piston c^2 will effect a simultaneous tilting of beam b against the action of spring e . As the beam is thus tilted, its projection b^2 in descending will push the cross-piece f^2 forward to tilt the yoke L . (Dotted lines in Fig. 4.) In this way the nose b^4 is withdrawn from underneath lever I , and the latter is released. The weight j will consequently be free to tilt lever I and carry its arm i^2 toward beam b , so that the arm i^2 will contact with the beam beneath its notch i^3 . The parts are brought into the above position at the beginning of the blowing operation and will be held in such position while the exhalation continues. As soon, however, as the exhalation is discontinued or interrupted the spring e will tilt the beam b to lower piston c^2 and cause the latter to assume its normal position intermediate the tubes f^1 and g^1 . As the beam is tilted in the manner described its left end will be raised and carried opposite the notch i^3 of lever-arm i^2 . The weight j will therefore tilt the lever I and carry notch i^3 underneath beam b , so that the latter is relocked in position, Figs. 2 and 3. The locking of beam b will cause a simultaneous locking of piston c^2 , and thus the communication between tubes f^1 and g^1 remains interrupted until the introduction of a new coin. It will be seen that immediately upon the cessation of pressure against the piston the latter will descend and be locked in this position to disconnect the inlet-tube from the indicator. Thus if the operator attempts to work the machine by two or more successive exhalations or impulses without the introduction of new coins such attempt will be frustrated.

What I claim is—

1. In a coin-controlled apparatus, the combination of a cylinder with an inclosed piston, a beam connected thereto, a coin-controlled lever engaging the same, and a pivoted frame

having a nose adapted to be projected beneath the lever, substantially as specified.

2. In a coin-controlled apparatus, the combination of a cylinder with an inclosed piston, a beam connected thereto, a coin-controlled lever having a notched arm adapted to engage the beam, and a pivoted frame having a nose adapted to be projected beneath the lever, substantially as specified. 45

3. In a coin-controlled apparatus, the combination of a beam having an inclined projection with a coin-controlled lever having a notched arm adapted to engage the beam, and a pivoted frame having a cross-arm adapted to engage the inclined projection, and a nose adapted to be projected beneath the lever, substantially as specified. 55

4. In a coin-controlled apparatus, the combination of a beam having an inclined projection, with a weighted coin-controlled lever having a notched arm adapted to engage the beam, and a weighted pivoted frame having a cross-arm adapted to engage the inclined projection, 65 and a nose adapted to be projected beneath the lever, substantially as specified.

5. In a coin-controlled apparatus, the combination of a cylinder with inlet and exit tubes communicating therewith, an inclosed piston, a beam connected thereto and having an inclined projection, a coin-controlled lever having a notched arm adapted to engage the beam, and a pivoted frame having a cross-arm adapted to engage the inclined projection, and a nose adapted to be projected beneath the lever, substantially as specified. 70

Signed by me at New York city, (Manhattan,) New York, this 8th day of January, 1904.

ARTHUR E. WELLS.
